UNITED STATES PATENT OFFICE.

CURTIUS COLBY, OF WILSON, NEW YORK.

EARTH-EXCAVATOR.

Specification of Letters Patent No. 17,669, dated June 30, 1857.

To all whom it may concern:

Be it known that I, CURTIUS COLBY, of Wilson, county of Niagara, and State of New York, have invented a new and useful Improvement upon Machines for Excavating Earth; and I do hereby declare that the following is a full, clear, and exact description of the construction and operation of the same, reference being had to the annexed drawings, making a part of this specification, in which—

Figure 1 is a perspective view; Fig. 2, a longitudinal elevation, and Fig. 3, a bird's-eye view.

15 B' B B are three wheels which support and carry the machine.

C is a cog wheel firmly attached to the inner end of the hub of the wheel B' and revolving with it. D is also a cog wheel of 20 the same diameter and fitted to mesh into the cog wheel C.

A is an iron shaft running horizontally across the top of the frame, to one end of which is firmly attached the cog-wheel D, 25 the other end being supported by a standard above the frame and playing loosely through the same. The opposite end of the shaft is supported upon the frame by being passed through one end of the lever F resting upon a fulcrum; the lever by 30 being depressed or elevated places the two cog-wheels in and out of gear.

E is a lever, being combined with the lever F at the point V, having attached at 35 one end a curved bar furnished on the under side with a catch or dog W and passing over the wheel D, said bar is attached to the frame by a pin at the end upon which it may turn.

40 H, H, are rollers or drums firmly attached to the horizontal bar A and revolving with it.

Y, Y, are chains attached each at one end to the drums H, H, thence descending 45 perpendicularly and attached at the other end to the metallic arms at S, S.

S S are the arms or immediate support of the excavator G. Said arms are supported upon the frame by means of a rod P passing 50 through the rear posts and through the upper rear part of the arms. The hind board of the excavator is firmly attached to the arms S S and detached from the sides and bottom. The sides and bottom are 55 firmly attached to each other and suspended to the arms by gudgeons or pivots at R R.

O is a lever connecting with a spring catch which holds the bottom and sides of the excavator in connection with its hind board.

I is a strap attached to the forward and rear parts of the side-board and passing over a roller L at the upper part of the frame.

N is a standard rising above the frame 65 work Q, through a slot in which the levers E and F are allowed to play, also containing notches to retain the lever F in its proper position during the operation of the machine.

T is a metal spring furnished with a notch for the purpose of holding the lever E in its proper position during the operation of the machine as will be shown below.

M is a seat for the operator of the machine.

K in Fig. 2, is a tiller for varying the direction of the machine.

In Fig. 1 the machine is represented ready to load. The long end of the lever 80 F has been placed in the lower notch in the standard, thus throwing the wheels C and D out of gear. The desired height of the nose of the dipper is regulated by the dog W on the wheel D being operated upon by 85 the lever E. After the excavator is filled with earth the lever F is raised into the upper notch in the standard which throws the wheels C and D into gear.

Owing to the combination of the levers E and F at V, 90 both are raised simultaneously. Thus by the raising the lever F and placing the wheels in gear the dog W in connection with the lever E is raised allowing the wheel D to revolve. The excavator is now in a position for elevating which is accomplished by the onward motion of the team i, i, the wheels C and D being in connection the 95

chains Y Y are wound up around the drum H H, thus elevating the excavator. In 100 consequence of the peculiar construction of the arms (or immediate support) of the excavator by which they are suspended from the frame at a point above the level of the top of the side boards the hind end is 105 elevated more or less simultaneously with the forward end. After being sufficiently elevated the levers E and F are caused to assume their former position by which means the wheels C and D are disconnected 110 and the excavator sustained at its elevation by the dog W setting between the cogs of

wheel D. The load can now be taken to any desired place of deposit. The earth is liberated by pressing the foot upon the lever O which acting upon the spring catch severs 5 the connection between the bottom and sides and the hind boards and the earth is deposited.

Fig. 2 represents the machine as having deposited its load or "dumped." The excavator is caused to reassume its position for 10 loading by pressing upon the spring T. The lever E is depressed undoing the wheel D. The excavator thus being free is brought down by its own gravity. The 15 strap I being attached to the front and rear ends of the side board and passing over the roller at L has the effect while the excavator is descending to bring the rear end of the bottom board up to the hind board when it 20 is caught by the spring catch O being then in the position as represented in Fig. 1. The operator may vary the direction of the machine to the right or left to suit circumstances by the action of the tiller K.

Fig. 3 is given to show the construction 25 more plainly.

I do not claim the mounting and using an excavator upon wheels nor suspending

its sides upon pivots or gudgeons neither for the escape of the earth by letting the 30 bottom free, as I am aware of there being machines used with these principles; neither do I claim the method of elevating the excavator by the cog wheels C and D acting upon the drums H H or the chains attached thereto, nor the method of varying the 35 direction of the machine by the tiller K. But

I do claim—

1. The use of the levers E and F with 40 their combination for the purposes as set forth.
2. The suspending the arms S S to the frame at a point P above the level of the top of the excavator, thus securing the elevation of the hind as well as fore part at 45 the same time.
3. Causing the return of the bottom of the excavator to its proper position for re-loading by means of the strap I and roller 50 L as described.

CURTIUS COLBY.
